SAFETY STARTER CIRCUIT AND UNIT

Irwin S. Jacobsen, Little Falls, N. J., assignor to
 Industrial Electronics Corporation, Newark,
 N. J., a corporation of New Jersey

Application June 21, 1947, Serial No. 756,186

10 Claims. (Cl. 315—100)

1

The present invention is concerned with safety starting units and with circuits incorporating the same for the protection of gaseous, electrical discharge devices such as fluorescent lamps of the hot cathode type.

It is among the objects of the invention to provide a unit of the above type which is relatively inexpensive, compact and economical in operation, requiring a minimum of parts and which lends itself for use with fluorescent lamps and the conventional fixtures thereof as a replacement for glow starters of conventional type, which does not draw current when the lamp is functioning normally and which assures the prompt elimination of the intermittent flashing on and off of a defective lamp, regardless of reasonable variations in ambient temperature, thereby not only avoiding the annoyance of such flashing but also safeguarding the starter unit itself from the destructive effect of such intermittent starting.

Another object is to provide a safety circuit for a starter unit of the above type which operates dependably and promptly to preclude the application of starting current to a defective lamp, and to maintain the lamp from flashing after the first few starting impulses have been applied thereto, regardless of normal variations in ambient temperature and which automatically restores itself promptly to permit normal operation of a new lamp substituted for the defective one.

A feature of the invention is a heat responsive switch arm connected at one end in circuit between a control resistor and a safety resistor, the pair of resistors being placed in series with each other and with a glow switch starter, the electrodes of a gaseous electric discharge device and a ballast coil. In a preferred embodiment shown, the switch arm short circuits the safety resistor from the circuit, both when the lamp is operating normally and when the circuit is not energized, that resistor functioning only with a defective lamp. In response to a prolonged starting current through the control resistor caused by repeated attempts to start a defective lamp, the switch arm is displaced, thus removing the short circuit from the safety resistor to bring it into action at such time only. The heating effect of the safety resistor will thereupon positively move the switch arm without floating thereof until it short circuits the glow switch and the control resistor effectively to remove them from the circuit. Continued current passing through the safety resistor which is preferably of high

2

ohmic resistance, produces sufficient heat to retain the switch arm in deflected position and thus retain the short circuit across the glow switch until the circuit is broken, thereby preventing the glow switch starter from starting or attempting to start the fluorescent lamp.

In the accompanying drawings in which are shown one or more of various possible embodiments of the several features of the invention:

10 Fig. 1 is a circuit diagram showing an embodiment of the safety starter circuit,

Fig. 2 is a front elevational view of the starter unit showing only the casing in cross section,

Fig. 3 is a side elevational view, similar to Fig. 2,

Fig. 4 is a rear elevational view similar to Fig. 2,

Fig. 5 is a transverse cross sectional view taken along line 5—5 of Fig. 4, and

20 Fig. 6 is a view similar to Fig. 5 taken along line 6—6 of Fig. 4.

Referring now to the drawings, there is shown in the diagrammatic view of Fig. 1 a conventional gaseous electric discharge device 10 of the hot cathode type such as a fluorescent lamp including a pair of electrodes 11 and 12 at opposite ends thereof. One of the mains 13 connected to electrode 11 has a ballast coil 14 in series therewith, while a switch 15 is shown in the other main 16, the latter being connected to electrode 12.

The starting circuit includes terminals 22 and 23 which are connected to electrodes 11 and 12 respectively of the lamp by leads 17 and 18. A 35 starter 19 which preferably is of the glow switch type has one of its electrodes 31 connected to terminal 22 and the other electrode 30 thereof to lead 44 of control resistor 43, the other lead 46 of which is connected to lead 40 of resistor 39, the other lead 41 of which latter resistor is connected to terminal 23. Thus starter 19, resistor 43 and resistor 39 are connected in series between terminals 22 and 23. The fixed end of a bi-metallic switch arm 32 is connected as shown 45 between resistors 43 and 39, for its free end to be movable between the contact ends of contact leads 36 and 37, respectively, connected to contacts 22 and 23. The free end 35' of switch arm 32 normally engages the contact end of lead 37, 50 so that resistor 39 is normally short circuited.

When switch 15 is closed, the line voltage will be applied across the electrodes 11 and 12 of the lamp and across terminals 22 and 23. As the applied voltage is at the outset insufficient to 55 cause arcing of the lamp 10 but sufficient to cause

glow switch starter 19 to ionize, current will flow through the circuit, establishing a magnetic field in the ballast coil 14, the collapse of which upon opening the circuit establishes the desired voltage. The path of current through the circuit will be through main 16, electrode 12, lead 18, terminal 23, contact arm 37, switch arm 32, lead 46, resistor 43, lead 44 through the glow switch starter 19, terminal 22, lead 17, electrode 11, ballast coil 14 and main 13. The heat developed by the ionization of the glow switch 19 will bring the contacts 30, 31 thereof together and close the gap therebetween, thereby stopping the glow. As soon as the glow ceases, the bimetallic contact 31 in the glow switch will cool and deflect, thereby causing the contacts of the glow switch to separate. This will break the starting circuit through the electrodes 11 and 12 and the ballast coil 14, causing the magnetic collapse and producing the voltage to discharge through the circuit. This sudden impulse should bridge the gap between the now heated electrodes in the lamp and start the arc, causing the lamp to light. Since the arc when once maintained requires voltage less than that required to initiate the glow discharge in the glow switch, the latter will remain out of action and the starting circuit is broken due to the gap between the contacts 30, 31 of glow switch 19. If the lamp is in normal condition, one or two cycles of the glow switch should light it.

At the same time that the contacts 30, 31 of the glow switch are closed but before the lamp lights, heat is generated in resistor 43 which will be dissipated to the bimetallic switch arm 32. If the lamp is defective, continued cycles of the glow switch 19 will produce sufficient heat in the resistor 43 to cause switch arm 32 to deflect to the position indicated in dashes in Fig. 1 so that the end 35 thereof is moved out of engagement with the contact 37, thereby removing the short circuit about resistor 39. That resistor will now draw current, the circuit being through main 16, electrode 12, lead 18, terminal 23, lead 41, resistor 39, leads 40 and 46, resistor 43, lead 44, glow switch 19 which is ionized, terminal 22, lead 17, electrode 11, ballast coil 14 and main 13. The combined heat from resistors 39 and 43 will cause switch arm 32 to be positively deflected until it is brought into engagement with contact 36 as shown in dot and dash lines in Fig. 1, and short circuit glow switch 19 and resistor 43, thereby effectively removing them from the circuit and thus placing resistor 39 directly across lamp electrodes 11 and 12. Continued passage of current through resistor 39 will produce sufficient heat to maintain the end 35 of switch arm 32 in engagement with contact 36, thus retaining the short circuit across the glow switch 19 and resistor 43 and effectively preventing the fluorescent lamp from starting, inasmuch as the glow switch starter is now out of the circuit. It is apparent that the short circuiting of the glow switch starter 19 will occur if the lamp does not light after a few cycles. Thus the rapid destruction of the glow switch 19, due to many repetitions of the starting cycle on a defective lamp, is avoided. Shortly after the circuit is broken by the opening of switch 15, or opening of circuit by lamp removal, resistor 39 will cool and allow switch arm 32 to revert to its normal position shown in Fig. 1, in readiness for normal operation with a replacement lamp.

Resistor 43 should have a relatively low ohmic value, to have available sufficient voltage across the open contacts of the glow switch, to initiate and maintain the glow discharge. In the embodiment herein, a "Nichrome" resistor is used, illus-

tratively of in the order of 15 ohms, which will determine the desired current flow. However, as it only requires a relatively small wattage to produce sufficient heat to maintain the switch arm 32 in deflected position, resistor 39 which in the embodiment herein is of carbon composition, should be of high ohmic value in the order of 20,000 ohms or more. Thus when the glow switch starter and resistor 43 are short circuited by switch arm 32 when the lamp is defective, and resistor 39 is placed across the electrodes 11 and 12, resistor 39 will draw but little current and thus will use but little power.

Among other advantages of the circuit is the fact that the instant the switch arm 32 disengages contact 37, the carbon resistor 39 is cut into circuit to become heated for the safety action to commence. That safety action is not interrupted for an instant, but current evolving effective heat is passed through resistor 39 throughout the period that switch arm 32 is in transit from contact 37 to contact 36 and thereafter. There is therefore no danger of inhibiting the safety action on low ambient temperature as in a cold room for instance. Sufficient heat will be developed by the heating of the carbon resistor 39 to ensure positive movement of the switch arm and to guard against the switch arm floating between contact arms 37 and 36, as it might if the safety action began only when switch arm 32 had been deflected all the way to a safety contact position.

A safety starter unit incorporating the starting and safety controls of the circuit shown in Fig. 1 and above described, is shown in Figs. 2 to 6 of the drawings wherein the numerals used in the circuit diagram of Fig. 1 are employed for corresponding elements. The unit which is connected across leads 17 and 18 from electrodes 11 and 12 respectively, comprises an insulating base 21 with two terminals 22 and 23 depending therefrom and a metal cover or cap 24 having tabs 25 removably to secure it to base 21. The cap 24 had an insulating liner 26 covering its side wall and a further insulating liner disk 27 for its top wall. In the unit is enclosed the insulating upstanding panel 28 rigidly affixed in the manner hereinafter set forth to terminal posts 22 and 23 and having mounted on one side thereof a starter 19 which preferably is of the glow switch type. This switch may be of conventional construction, involving a glass tube 29 filled with noble gas, such as neon for instance, and having electrodes 30 and 31, one of which is U-shaped and of bimetallic material responsive to variations in temperature. The other components of the safety starter unit are disposed on the side of panel 28 opposed to the glow switch starter 19 and comprise a bimetallic switch arm 32, preferably in the form of a leaf which is secured near the upper end thereof to panel 28 by the laterally extending arm 33 of a metal clip 34, said arm pressing the end of switch arm 32 against the panel. Clip 34 has tabs 35 unitary therewith extending through and bent over rigidly to affix it to the panel 28. The switch arm 32 extends downward the length of the panel and has a wire contact 35 at its end which normally engages a contact bar 37 affixed at one end by tabs 37' to said panel and spaced therefrom.

A contact bar 36 in juxtaposition to contact bar 37 and slightly spaced therefrom, is affixed at one end to the panel by tabs 38 and connected to terminal post 22. Contact bars 36 and 37 straddle the wire contact 35 of switch arm 32,

the wire contact 35 being normally in engagement with contact bar 37 and free to move between contact bars 36 and 37. The said contacts are preferably of silver or silver plated for low resistance and the inhibition of arcing.

Positioned alongside switch arm 32 is carbon resistor 39, one terminal wire 40 of which is soldered to metal clip 34, while the opposite terminal wire 41 is soldered to the tab end 37' of contact arm 37 and passes through panel 28 to be connected to terminal 23 as at 42 to provide a rigid support for one bottom corner of the panel.

Lead 47 of the glow switch starter 19 is soldered to the tab end 38 of contact arm 36 and passes through panel 28 to be connected to terminal 22 as at 47' to provide a rigid support for the other bottom corner of the panel while lead 48 of the glow switch starter 19 extends through an eyelet 45 affixed to the panel at the top thereof.

Positioned near the upper end of switch arm 32 is "Nichrome" resistor 43, lead 46 thereof being soldered to metal clip 34 while lead 44 thereof extends through eyelet 45 and is soldered thereto lead 48 of the glow switch starter 19.

It will be understood that the spring tension of switch arm 32 is such as to maintain contact wire 35 thereof against contact arm 37 even at the highest temperature encountered in any place where a fluorescent lamp is normally installed or which is generated by the heat of a normally operating lamp. Thus it can be seen that the control resistance 43 serves the double function of determining the voltage across the glow switch starter 19 and of initiating the movement of the thermal switch arm 32 in the repeated attempts to start a defective lamp. The safety resistance 39 thereby put in circuit together with resistance 43 effectively move the thermal switch arm 32 to contact arm 36 for short circuiting the starter unit and its control resistance 43 and do so with a minimum of current which flows therethrough as long as the defective lamp remains in circuit. The system and unit are therefore simple, economical or current and thoroughly reliable in action inasmuch as floating or hunting of the thermal switch arm 32 between its contact bars 36 and 37 is precluded, the thermal switch arm 32 remaining in its normal position as long as the controlled lamp is in order and once it leaves contact bar 36 it moves positively to the starter short circuiting position.

As many changes could be made in the above circuit and construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. A safety starting and operating circuit for gaseous electric discharge devices equipped with spaced electrodes comprising a starting circuit for passing current through said electrodes in series, said circuit comprising a pair of resistors connected in series between said electrodes, a thermally responsive switch arm in proximity to both of said resistors and connected at one end therebetween, and a starter in the series circuit between the connected end of said switch arm and one of said electrodes, intermittently to interrupt said starting circuit, said switch arm be-

ing deflected by the heating of said resistors to short circuit said starter, thereby stopping the intermittent interruption of said starting circuit.

- 5 2. A safety starting and operating circuit for gaseous electric discharge devices equipped with spaced electrodes comprising a starting circuit for passing current through said electrodes in series, switch means intermittently to interrupt said starting circuit, a pair of resistors in series with said switch means and said starting circuit, and a heat responsive switch arm normally short circuiting one of said resistors, said switch arm being deflected by the heating of the second of 10 said resistors during the operation of said switch means to remove the short circuit from the first of said resistors and place the latter in the circuit, said switch arm being further deflected by the continued operation of said switch means to 15 short circuit the second of said resistors and said switch means, said first resistor evolving sufficient heat to maintain said switch arm in deflected position, thereby stopping the intermittent interruption of said starting circuit.
- 20 3. The circuit as claimed in claim 2 in which the means intermittently to interrupt said starting circuit comprises a starter of the glow switch type.

- 25 4. In a safety starting and operating circuit 30 for a gaseous electric discharge device equipped with spaced electrodes, a starting circuit for passing current in series between said electrodes, means automatically to interrupt said circuit to strike an arc between said electrodes and means 35 to preclude the sustained intermittent starting of a defective lamp, said latter means comprising a thermally operated switch arm normally in said starting circuit, a safety resistor in said starting circuit normally short circuited by said 40 switch arm, a control resistor in said starting circuit normally in series with said switch arm, said switch arm being deflected by the heat evolved in said control resistor in the attempted starting of a defective lamp to remove the short 45 circuit across said safety resistor, the heat evolved by said safety resistor in the continued attempted starting of a defective lamp deflecting said switch arm further to short circuit said control resistor and said means automatically to 50 interrupt said starting circuit, thereby preventing further attempts to start said lamp.

5. A safety starting and operating circuit for gaseous electric discharge devices equipped with spaced electrodes comprising a starting circuit 55 for passing current through said electrodes in series, a pair of starting contacts in said starting circuit, a pair of heater means in said starting circuit, a heat responsive switch arm connected at one end between said pair of heater 60 means and normally short circuiting one of said heater means, the second of said heater means evolving sufficient heat in the attempted starting of a defective lamp for displacement of said switch arm to remove the short circuit across 65 said first heater means, said first heater means evolving sufficient heat in the continued attempt to start said lamp to displace said switch arm further to short circuit said second heater means and said pair of starting contacts, said first 70 heater means maintaining said switch arm in displaced condition as long as the circuit remains closed, thereby preventing further attempts to start said lamp.

6. A self contained safety starter unit for a gaseous electric device, said unit comprising a sup-

port base having a pair of terminal posts, an insulating panel rising therefrom, an eyelet affixed to said panel, a bimetallic switch arm, a clip affixed to said panel and rigidly clamping one end of said switch arm thereagainst, a wire contact at the free end of said switch arm, a pair of spaced contacts affixed to said panel in the path of movement of and straddling said wire contact, one of said spaced contacts being normally engaged by said wire contact, a resistor positioned in close heat transfer relation to said switch arm at the affixed end thereof having one of its leads connected to said clip and the other of its leads connected to said eyelet, a second resistor positioned alongside said switch arm having one of its leads connected to said normally engaged spaced contact and to one of said terminal posts and the other of its leads affixed to said clip, a glow switch starter having a pair of contacts, one of its contacts being connected to the other of said terminal posts and to the other of said spaced contacts, and the other contact of said starter being connected to said eyelet.

7. A panel unit for a safety starter unit, said panel unit having a glow switch starter on one side thereof having a pair of contacts, a bimetal switch arm on the other side of said panel having a contact end, a metal clip for said switch arm affixed to said panel and rigidly holding one end of said switch arm thereto, a resistor having a pair of leads and positioned in close heat transfer relation to the affixed end of said switch arm, one of the leads from said resistor being connected to said metal clip and the other lead from said resistor being connected to one of the contacts of said starter, a contact bar affixed at one end to said panel and connected to the other contact of said starter, a second contact bar also affixed at one end to said panel and adjacent to and spaced from said first contact bar, said contact bars being in the path of movement of said contact end, said contact end normally engaging said second contact bar and spaced from said first contact bar, a composition resistor positioned alongside said switch arm and having a pair of leads, one of the leads being connected to said metal clip and the other of said leads being connected to said second contact bar.

8. A safety starter unit for a gaseous electric discharge device having a pair of spaced electrodes, said unit comprising a pair of terminals, a bimetal switch arm, a support therefor at one end thereof, a pair of spaced contacts both in the path of movement of the outer end of said switch arm and straddling said outer end, one of said contacts being normally engaged by said outer end and the other of said contacts being normally spaced from said outer end, a pair of resistances

each having a pair of leads, said resistances being in close heat transfer relation to said switch arm, one of said resistances having a lower ohmic value than the other, one of the leads from each of said resistances being connected to said switch arm, the other lead of the resistance of higher ohmic value being connected to one of said terminals and to the normally engaged contact, a glow switch starter having a pair of contacts, one of its contacts being connected to the other end of the resistance of lower ohmic value and the other of its contacts being connected to the other of said contacts of said pair of contacts and to the other terminal.

15. In a starting and operating circuit for gaseous electric discharge devices equipped with spaced electrodes, a starting circuit for passing current through said electrodes in series, said starting circuit including a pair of starter contacts, means automatically to open said contacts when the arc across the electrodes is struck, and to maintain them open while the arc exists, a thermally responsive arm in said circuit, a control resistor passing the starting current and generating the heat to deflect said arm to interrupt said starting circuit in the attempted starting of a defective lamp, a safety resistor normally out of circuit, said thermally actuated arm, when deflected, connecting said safety resistor in said 20 starting circuit, said safety resistor deflecting said arm further in the continued attempted starting of said defective lamp, and cutting said pair of starter contacts and said control resistor out of circuit, said safety resistor generating sufficient 25 heat to maintain said thermally responsive arm in deflected position as long as the circuit remains closed.

30. The combination set forth in claim 9 in which said control resistor has a low ohmic resistance of from 10 to 20 ohms and said safety resistor has a relatively high ohmic resistance of from 20,000 to 50,000 ohms.
